TRUNDEL TOY

Paul A. Fuld, Glen Burnie, Md.

Application March 30, 1945, Serial No. 585,624

4 Claims. (Cl. 46—114)

The invention relates to toys and has as an object the provision of a child's toy having an attractive changeable appearance combined with means for producing sounds.

It is an object of the invention to provide a trundle toy having ground wheels producing a changeable appearance when pushed along a floor and having means operated by the floor engaging wheels to produce sounds.

Further objects will appear from the following description when read in connection with the accompanying drawings showing an illustrative embodiment of the invention and wherein:

Figure 1 is a side elevation.

Fig. 2 is a plan view.

Fig. 3 is a vertical section on line 3—3 of Figure 1.

Fig. 4 is a vertical section on line 4—4 of Fig. 2 showing operative positions of a part in dotted lines.

Fig. 5 is a vertical section similar to Fig. 4 partly broken away and showing a different position of parts.

As shown the device comprises a pair of floor engaging wheels 10 and 11 each shown as formed with annular grooves 12, 13 respectively with pins 14 extending across the grooves near the periphery of the floor engaging wheel. Loosely mounted upon the pins 14 are a series of rings 15 which hang by gravity on the pins while at the upper portion of the wheels and which rings engage the floor when the device is trundled therealong to cause them to disappear into the grooves 12.

It will be seen that when the device is trundled along the floor with some speed, centrifugal force will cause the rings 15 to swing out into view a distance depending upon the speed of movement. The wheels 10 and 11 are desirably fixed upon the axle 16 for keeping the device in assembly and to preserve their circumferential relationship. To provide for motion of the device as a trundle toy, a block 17 is mounted loosely on the axle 16 and a tongue 18 is shown as inserted in an opening in the block 17 in the manner shown in Fig. 5. To produce sound a pair of similar blocks 19, 20 are shown loosely mounted upon the axle 16, washers being placed upon each side of each block 19, 20 to insure free movement thereof upon the axle uninfluenced by friction with the wheels 10 and 11 or the block 17.

Carried by the wheels 10 and 11 are a pair of pins 21, 22 preferably at an angle of 180° each to the location of the other. The blocks 19 and 20 are shown as eccentric with the shaft 16 so as to provide a heavier and lighter end of each. The

long ends of the blocks stand in the path of the pins 21, 22 respectively and as the ground wheels 10 and 11 revolve to bring the respective pins against the long ends of the blocks 19 and 20, the blocks will be forced to revolve with the wheels until they are carried above a position of a vertical line through the axis, whereupon they will fall by gravity away from the pin to the position of the block 19 shown in Fig. 3. The pins 21, 22, as they pass above the blocks 19, 20, when the latter are in the position of block 19 in Fig. 3 will pass over the shorter end of the block. The result will be repeatedly recurring clicking sounds as the pins contact the blocks 19, 20 successively.

15 The device is made more attractive by coloring the different parts with different colors. The ring 15 may be made each of a different color and the blocks 19, 20 colored still further differently and the ground wheels 10 and 11 may be ornamented on their outer surfaces. The combined result of the movable parts, the color, and the sound producing means provide a toy very attractive to small children.

20 Minor changes may be made in the physical embodiment of the invention within the scope of the appended claims without departing from the spirit of the invention.

I claim:

30 1. A trundle toy comprising, in combination: a trundle wheel; a pin carried by said wheel adjacent its periphery and extending parallel with the axis of rotation of the wheel; an annular ring member loosely supported on said pin, the radial thickness thereof being less than the spacing of its pin support from the tread of the wheel; whereby the ring may be thrown to positions 35 radially outward of the tread of the wheel by centrifugal force and to a position radially inward of the tread by contact with the ground; and means to retain the ring on its supporting pin.

2. A trundle toy comprising, in combination: a trundle wheel formed with an annular, peripheral groove; a plurality of pins extending across the groove and spaced from the periphery of the wheel; an annular ring with a relatively large opening supported on each pin within said groove; the radial thickness of each ring being less than the spacing of its pin from the periphery of the wheel.

3. A trundle toy comprising, in combination: an axle; a tongue projecting therefrom; a peripherally grooved wheel carried by each end of the axle for revolution upon a supporting surface; a plurality of pins traversing the groove of each wheel at locations spaced from the periphery of

the wheel; an annular ring loosely mounted on each pin for motion between positions wherein the rings project from the peripheries of the wheels and positions of complete enclosure in the grooves.

4. The combination of claim 3 with a rod projecting from a face of one of the wheels, and a member freely revoluble on the axle, said mem-

ber projecting different distances from the axle at its respective ends, the longer end being contacted by said rod as the wheel revolves and the shorter end clearing the rod as the member revolves, whereby to provide a combined visual and sound effect.
